UNITED STATES PATENT OFFICE.

JAMES J. THOMAS AND LILLIAN L. VAUGHAN, OF RALEIGH, NORTH CAROLINA.

SCREEN OR WINDOW LOCK.

1,257,051.

Specification of Letters Patent. Patented Feb. 19, 1918.

Application filed January 27, 1917. Serial No. 144,851.

To all whom it may concern:

Be it known that we, JAMES J. THOMAS and LILLIAN L. VAUGHAN, are citizens of the United States, residing at Raleigh, in the county of Wake and State of North Carolina, have invented certain new and useful Improvements in Screen or Window Locks; and we do hereby declare the following to be a full, clear, and exact description of the invention, such as will enable others skilled in the art to which it appertains to make and use the same.

This invention relates to a lock and has for one of its objects the provision of a device of this character especially adapted for use in locking two parts together, such as a window sash to a window frame or a screen to a window frame and which will prevent any undue movement of the parts locked together, thereby obviating raveling of window sashes or screens.

Another object of this invention is to provide a keeper secured to the window frame or permanent object and adapted to receive an eccentric catch carried by the movable part such as the window sash or screen, whereby the parts are locked together and which catch can not be operated by a knife blade or similar tool.

A further object of this invention is to provide a casing secured to the movable object in which the catch is journaled and has a spring secured therein adapted to bear against the catch at all times to prevent accidental movement of the catch either in an active or inactive position.

A still further object of this invention is the provision of a screen or window lock of the above stated character, which shall be simple, durable and efficient, and which may be manufactured and sold at a comparatively low cost.

With these and other objects in view as will become more apparent as the description proceeds, the invention consists of certain novel features of construction, combination and arrangement of parts as will be hereinafter more fully described and claimed.

For a complete understanding of my invention, reference is to be had to the following description and accompanying drawing, in which:

Figure 1 is a vertical sectional view illustrating the application of our lock to a permanent and movable object.

Fig. 2 is a sectional view of the same taken on the line 2—2 of Fig. 1.

Fig. 3 is a plan view of the keeper, and

Fig. 4 is a perspective view of the key. 60

Fig. 5 is a fragmentary front elevation of a window frame and sash, illustrating our invention applied thereto.

Fig. 6 is a detail sectional view illustrating the metal ferrule. 65

Referring in detail to the drawing, the numeral 1 indicates a stationary object such as a window frame or the like and the numeral 2 indicates a movable object, such as a window sash, screen or a door, which parts 70 have our improved lock applied thereto.

The permanent object 1 is provided with a recess 3 for receiving a cup-shaped keeper 4, which has formed on each end thereof, extensions 5, which are apertured to receive 75 screws or like fasteners 6 for securing the extensions to the permanent object 1. The cup-shaped keeper 4 has its side walls connected by a bar 7 adapted to be engaged by an eccentric catch 8.

The movable object 2 is provided with a recess in which is positioned a casing 9, having a movable cover 10. The movable cover 10 and the rear wall of the casing 9 is provided with alining apertures to receive a 85 hub 11 having a squared opening or aperture 12. Formed upon the hub 11 is a right angled enlargement 13 on which an arcuate extension 14 is formed, which forms the eccentric catch 8. 90

A leaf spring 15 is secured to the top wall of the casing and upon the interior thereof as illustrated at 16. The leaf spring 15 is bent rearwardly upon itself as illustrated at 17 and has its free end bearing upon the eccentric catch 8 to hold said eccentric catch 8 against accidental movement. 95

A key 18 has one end twisted to form a finger grip 19 and has secured to its opposite end a squared lug 20 which is adapted 100 to be inserted within the squared opening 12 of the hub 11 for rotating the eccentric catch 8 causing said eccentric catch 8 to move into the keeper 4 under the bar 7, locking the stationary and movable parts together. 105

As the eccentric catch 8 is moved into the keeper 4, the free end of the leaf spring 15 moves downwardly with the eccentric catch and prevents the eccentric catch from being accidentally moved from within the keeper 4. 110

From the foregoing description taken in connection with the accompanying drawing,

it will be noted that a lock has been provided which will efficiently lock two parts together and which cannot be operated by a knife blade or like tool by inserting it between the casing and the keeper. It being necessary to operate the eccentric catch by a key of the character heretofore described.

The window sash 18 mounted in the window frame 19 may be mortised or provided with a recess for the reception of the casing 9 as illustrated at 20 in Figs. 5 and 6, thus hiding the casing 9 from view. A metal ferrule 21 may be applied to the front face of the window sash 18 for permitting the lug 20 upon the key to be inserted within the eccentric catch for rotating the same into and out of engagement with the keeper. A plurality of keepers 22 may be mortised within the window frame 19 whereby the window sash 18 may be locked at various positions or in opened or closed position.

While we have shown and described the preferred embodiment of our invention, it will be understood that minor changes in construction, combination and arrangement of parts may be made without departing

from the spirit and scope of the invention as claimed.

What is claimed is:

A lock comprising a casing having one end wall open, a keeper associated with the open end of the casing, a hub journaled in the casing and having a squared opening to receive a key, a right angled enlargement formed on said hub, an arcuate shaped extension formed on said enlargement and adapted to be moved out of the open end of the casing into engagement with the keeper, and a spring secured to said casing and normally engaging the extension when within said casing and adapted to engage the right angled enlargement when said extension is moved into engagement with the keeper to prevent the extension from becoming disengaged from the keeper.

In testimony whereof we affix our signatures in presence of two witnesses.

JAMES J. THOMAS.
LILLIAN L. VAUGHAN.
